UNITED STATES PATENT OFFICE.

HERMAN J. FISHER AND ARTHUR BETZ, OF PASADENA, CALIFORNIA, ASSIGNEES TO
CROWN GAS RADIATOR COMPANY, OF PASADENA, CALIFORNIA, A CORPORATION OF
CALIFORNIA.

GAS RADIATOR.

Application filed November 15, 1922. Serial No. 601,010.

To all whom it may concern:

Be it known that we, HERMAN J. FISHER and ARTHUR BETZ, citizens of the United States, residing at Pasadena, in the county of Los Angeles and State of California, have invented certain new and useful Improvements in Gas Radiators, of which the following is a full, clear, and exact specification.

This invention relates to gas radiators or heaters, and is designed as an improvement on the structure disclosed in the patent of Samuel Toles, No. 1,438,412 issued December 12, 1922.

The main object of the present invention is to improve the circulation of the heated air in the larger sizes of radiators. To this end provision is made for promoting a more uniform circulation through the interior of the radiator, and for insuring the proper venting of the air so that adverse down drafts which might smother the flames of the burner are avoided. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a front elevation of a radiator constructed substantially in accordance with this invention.

Figure 2 is an end view thereof.

Figure 3 is a rear elevation of the same.

Figure 4 is a central vertical section through the radiator.

Figure 5 is a vertical section on the line 5—5 of Figure 4.

Figure 6 is a vertical section on the line 6—6 of Figure 4, and

Figure 7 is a section similar to that illustrated in Figure 5 showing a modified construction of end section.

The radiator may consist of two end sections 1 and 2, an intermediate vent section 3, and any desired number of filler sections

4 arranged between said end sections and vent section. All of the sections communicate with one another near the bottom through passages 5 and near the top through passages 6, said passages being formed by 55 interfitting collars 7 and 8, respectively. Between the passages 5 and 6, the sections are spaced apart, as at 9 in Figures 1, 3 and 4, to increase the radiating surface of the radiator. Bolts 10 are passed through all of the 60 sections near the top and bottom thereof for fastening said sections together, said bolts being preferably arranged in the passages 5 and 6.

The end sections 1 and 2 are made alike, 65 each having legs 11 for supporting the radiator above the floor. As best shown in Figure 5, the end sections have transverse passages 12 formed therein through which air may freely pass from the ends of the radiator into the spaces 9 between said end sections and adjacent filler sections 4. Four of said air passages 12 are shown in each end section, two being arranged side by side about midway of the height of the section, 70 while the other two are disposed side by side nearer the top of the section and in vertical alinement respectively with the lower two. Each end section is thus divided into a central column 13, a rear column 14 and 75 a front column 15, said columns being generally in the form of vertical cylindrical tubes which communicate with each other across the central portion of the radiator between the walls of the lower and upper 80 transverse passages 12. It will be noted that the passages 5 and 6 through which the several sections communicate with each other are arranged in the central column 13 of the end sections.

A partition 16 extending from the rear wall of each end section to the rear one of the lower pair of passages 12 cuts off the bottom of the rear column 14 from the passages 5, but the front column 15 is in communication with said passages 5 below the front one of said lower passages 12. A curved partition 17 follows the upper edge of the passages 6 and extends from one to the other of the upper pair of passages 12, so 100

that communication between the front and rear columns and the central column is cut off at the top of the radiator. Communication between said front and rear columns is 5 also interrupted at the top of the radiator by a vertical partition 18 extending from the center of the curved partition 17 to the top wall of each end section. A U-shaped partition 19 is arranged with its base extending 10 between the upper and lower pairs of passages 12 and its arms extending upwardly about centrally of the front and rear columns 14 and 15 and terminating below the top of each end section but preferably above 15 the curved partition 17.

Each of the filler sections 4 is constructed exactly like the end sections just described, except that said filler sections do not have the legs 11 or the air intake passages 20 which are arranged in the inner faces of said end sections below the passages 5. Air may enter the filler sections indirectly from the end and vent sections and also directly via openings or intakes 40 in 25 the bottom of said filler sections.

The intermediate vent section 3 of the radiator, as best illustrated in Figures 4 and 6, is divided into three columns corresponding to those of the end and filler sections by 30 vertical transversely extending air passage 21 in line with the front upper and lower passages 12 in the end sections, and a partition 22. A curved partition 23 follows the upper edge of the passages 6 and extends 35 from the passage 21 to the partition 22 thereby cutting off communication by either of the front or rear columns 24 and 25, respectively with the central column 26 at the top of the vent section. Communication be- 40 tween the three columns at the bottom is also cut off by a partition 27 which extends from the bottom of the passage 21 to the rear wall of the vent section. In the rear edge of the 45 vent section a vent opening 28 is arranged about midway of the height thereof and below said main vent opening 28, which is designed to be connected by pipe (not shown) to a chimney, there is a small auxiliary vent opening 29. The partition 22 50 may be of irregular form, as shown in Figure 6, and terminated preferably opposite the horizontal median line of the main vent opening 28. An air intake 30 is formed in the base of the vent section in line with the central column 26 and below the passages 5.

A burner pipe 31 extends through the passages 5 from one end of the radiator to the other and may have a pair of jet openings 32 and 33 arranged centrally of each radiator section. The openings 32 are in the top of the burner pipe, so that the flames therefrom are projected in line with the central columns of the radiator sections, as shown in Figures 5 and 6. The jet openings 33 are 65 in the side of the burner pipe facing the

front of the radiator and are preferably arranged at about 45 degrees from the jet openings 32, so that the flames from the openings 33 are projected into the front columns of the radiator. No jet openings are 70 provided in the rear face of the burner pipe because it is not desirable to heat up the rear columns of the radiator to the same extent as the central and front columns, said rear columns being placed next to the wall of 75 the room. The partitions 16 and 27 prevent the hot air from passing directly into said rear columns at the bottom, so that the heat must pass to the upper portion of the radiator before entering the rear columns thereof. 80

In the end and filler sections the heated air rising in the central columns between the walls of the lower pair of passages 12 strikes the base of the U-shaped partitions 19 and is carried to the outer portions of the front columns and rear columns, and after passing along the arms of said U-shaped partitions to the tops thereof, said heated air or fumes pass down along the inner faces of said arms of the U-shaped partition through the 85 inner portion of each of said front and rear columns to points below the upper pair of passages 12 where said fumes enter the central columns and pass up therein between said upper pair of passages 12 to the venting 90 passages 6 to the vent section 3. The provision of the U-shaped partitions 19 in said end and filler sections is especially advantageous in the larger sizes of radiators for the extra circulation of the air or fumes around 95 said partition retains said fumes or gases in the radiator a longer period of time, thereby giving greater efficiency for the amount of 100 gas burned.

In the vent section 3, the heated air rises 105 in the front column, passes across the top of the section above the curved partition 23, down the rear column along the rear face of the partition 22 and escapes through the main vent opening 28 to the chimney. This short and direct path of the air or fumes to the vent opening in the vent section insures the better venting of the end and filler sections because a draft is caused in the central column of the vent section between the walls 110 of the passage 21 and the partition 22 which draws the spent fumes from said outer sections and prevents back pressure which might tend to smother the flames. To further prevent back pressure originating in the 115 vent section, the auxiliary vent passage or opening 29 is provided below the main vent passage 28 as already described. This auxiliary vent opening gives the back pressure 120 a chance to relieve itself rather than put the pressure against the oncoming fumes or gases which might otherwise check the flames.

A modified form of end section is illustrated in Figure 7, it being understood that 125

the same construction and arrangement of air passages may be used in filler sections if desired. In this form of the invention instead of the U-shaped partition 19 shown in Figure 5 a substantially U-shaped partition 34 is arranged with its base extending between the upper pair of passages 12 and the curved partition over the passages 6. It will be noted that said curved partition 35 in Figure 7 has its lower ends spaced above the walls of said upper pair of passages 12 and that the base of said U-shaped partition 34 extends through these spaces leaving passages 36 between it and said curved partition 35 as well as passages 37 between said base of the U-shaped partition and the upper pair of passages 12. A vertical partition 38 extends from the center of the curved partition 35 to the top of the radiator section and corresponds to the partition 18 in Figure 5.

In the operation of the modified form of the invention the heated air from the burner rising in the central column is deflected by the base of U-shaped partition 34, which may be V-shaped as shown, and passes through the passages 37 to the upper portions of the front and rear columns. After passing upward along the outer faces 30 of the arms of said U-shaped partition to the top of the section, the heated air or fumes move downward along the inner faces of said arms and escape through the vent openings 6 to the adjacent sections via the 35 passages 36. This modified construction is designed particularly for very large radiators in order to give the burnt gases or fumes a little freer movement than in the other form and insuring the evacuation of 40 said gases without congestion at the vent.

The burner pipe may be equipped with the usual air mixer 39 and valve 40, see Figures 1, 2, 3 and 4. The end section adjacent said valve is provided with a lighting opening 41 normally closed by a swiveled cover 42.

As illustrated in Figures 1, 2 and 3, a guard 43 may be supported at a short distance in front of the radiator to prevent 50 children or other persons from accidentally coming in contact with said radiator and being burned thereby. As shown, said guard consists of a plurality of spaced vertical rods 44 conforming substantially to the 55 straight front edges of the radiator sections and the curved upper corners of the same. Alternate ones of said rods are preferably arranged to register with the ribbed edges of the radiator sections and extend 60 above and partially across the tops of said sections, while the other rods may be shorter and arranged in line with the spaces 9 between the sections.

The guard is supported in position on 65 the radiator by an upper transverse bar 45

which is rigidly fastened in any suitable manner to the vertical rods 44 and to the radiator. As shown, the ends of said bar 45 are bent inwardly to embrace the radiator and have their extremities turned down, 70 as at 46 to engage perforated lugs 47 cast or otherwise secured to the ends of the radiator. The bent ends of the bar 45 are long enough to space the upper portion of the guard a suitable distance in front of 75 the radiator. The lower end portion of the guard is spaced a corresponding distance from the radiator by a lower cross bar 48 rigidly secured to the vertical rods 44 and having rebent or looped end portions to 80 bear against the front edges of the end sections 1 and 2. The turned down extremities of the bent ends of the bar 45 may be detachably engaged with the lugs 47 so that the guard may be readily applied to and 85 removed from the radiator as desired.

We claim:—

1. In a radiator of the character described, a vertical section having three circulating columns communicating with one another 90 intermediate their ends, a burner in the lower part of the section, there being an air intake opening in the lower portion of said central column and an air vent opening in the upper portion of the same, a partition 95 extending over said vent opening and cutting off direct communication of the front and rear columns therewith, and a U-shaped partition having its base arranged across the intermediate communicating portions of 100 the three columns, the arms of said U-shaped partition extending upward in the front and rear columns to points opposite said partition arranged over the vent opening for the purpose specified. 105

2. In a radiator of the character described, a vertical section having three circulating columns communicating with one another intermediate of their ends, a burner in the lower part of the section, there being a vent in the upper portion of the central column, a partition extending over said vent and cutting off direct communication of the front and rear columns with said vent at the top 110 of the radiator, a partition extending from the vent bridging partition to the top of the section for separating the front and rear columns from each other at the top, and means for causing upward and downward circulation of heated air in the upper portions of the front and rear columns. 115

3. In a radiator of the character described, a vertical section having three circulating columns communicating with one another intermediate of their ends, a burner in the lower part of the section, there being a vent in the upper portion of the central column, a partition bridging said vent and cutting off the upper portions of the front and rear columns therefrom, a partition extending 120

from said vent bridging partition to the top of the section for separating the upper ends of the front and rear columns from each other, and a **U**-shaped partition having its 5 base arranged across the intermediate communicating portions of the three columns, the arms of said **U**-shaped partition extending upward in the front and rear columns for causing upward and downward circulation 10 of heated air in said columns.

4. In a radiator of the character described, a section having three vertical circulating columns, a burner in the lower portion of the section, there being a vent in the section above 15 the burner, means for interrupting the upward circulation of heated air in the central column and upward circulation of said air in the upper portion of the central column, and means for causing an upward and downward circulation of heated air in the upper portions of the front and rear columns.

5. In a radiator of the character described, a section having three vertical circulating columns, a burner in the lower portion of 25 the section, there being a vent in the section above the burner, and means for causing upward and downward circulation of heated air in the upper portions of the front and rear columns and upward circulation of said 30 air in the upper portion of the central column before reaching the vent.

6. In a radiator of the character described, a section having three circulating columns communicating with one another at an intermediate point and cut off from communication with each other at their upper ends, and means for causing upward and downward circulation in the upper portions of the front and rear columns.

40 7. In a radiator of the character described, a section having three circulating columns communicating with one another at an intermediate point, a burner in the lower portion of the section, there being a vent in the section above the burner, means for cutting off 45 communication between said columns at their upper ends, and means for causing upward and downward circulation of heated air in the upper portions of the front and rear columns and upward circulation of 50 said air in the upper portion of the central column before reaching the vent.

8. In a radiator of the character described, a section having three circulating columns, 55 sectional partitions separating said columns from one another, said sections of the partitions being spaced apart intermediate of the vertical extent of the columns, a burner in the lower portion of the central column, there being a vent in the upper portion of said central column, means for cutting off communication between the front and rear columns and the central column at the top, and means for interrupting the upward cir-

culation of heated air in the central column, 65 causing said heated air to circulate upwardly and downwardly in each of the front and rear columns, and finally permitting said heated air to circulate upwardly again in the central column to the vent. 70

9. In a radiator of the character described, a vent section having three circulating columns, a burner in the lower portion of the section, an intake in the upper portion of the central column, means for cutting off 75 communication between the front and central columns except through the rear column, a vent at an intermediate point in the rear column, and means for cutting off communication between said rear column and central 80 column except on the level with said vent.

10. In a radiator of the character described, a vent section having three circulating columns, a burner in the lower portion of the section, an intake in the upper portion 85 of the central column, means for cutting off communication between said front and central columns except through the rear column, a vent in rear column below the intake, means for cutting off communication between 90 said rear and central columns except at the level of said vent, and an auxiliary vent adjacent the previously mentioned vent for the purpose specified.

11. In a radiator of the character described, a vertical section having three circulating columns communicating with one another intermediate of their ends, a burner in the lower part of the section, there being an air intake opening in the lower portion 100 of said central column and an air vent opening in the upper portion of the same, a partition extending over said vent opening and cutting off direct communication of the front and rear columns therewith, and means for 105 causing upward and downward circulation of heated air in the upper portions of each of the front and rear columns.

12. In a radiator of the character described, the combination with a venting section, of a burner in its lower portion, partitions separating said section into three circulating columns, there being an inlet opening in the upper portion of the central column, a partition bridging said inlet opening and cutting off direct communication of the front and rear columns therewith, said rear column having a vent opening arranged below the inlet opening, the partition separating the central and rear columns extending from said bridging partition to a point opposite said vent opening. 110

13. In a radiator of the character described, the combination with a venting section, of a burner in its lower portion, partitions separating said section into three circulating columns, there being an inlet opening 115 in the upper portion of the central

column, a partition bridging said inlet opening and cutting off direct communication of the front and rear columns therewith, said rear column having a vent opening arranged below the inlet opening, and the partition separating the central and rear columns extending from said bridging partition to a

point opposite said vent opening and being of irregular contour for the purpose specified.

In testimony whereof we have signed our names to this specification.

HERMAN J. FISHER.
ARTHUR BETZ.
